UNITED STATES PATENT OFFICE.

BENJAMIN HUCHBERGER, OF CHICAGO, ILLINOIS.

DESIGN FOR A RING-SETTING FOR PRECIOUS STONES.

42,286.

Specification for Design.

Patented Mar. 12, 1912.

Application filed December 4, 1911. Serial No. 663,930. Term of patent 14 years.

To all whom it may concern:

Be it known that I, BENJAMIN HUCHBERGER, a citizen of the United States, residing at Chicago, in the county of Cook, State of Illinois, have invented a new, original, and ornamental Design for Ring-Settings for Precious Stones, of which the following is a specification, reference being made to the accompanying drawing, forming part thereof.

Figure 1 is a perspective view of a ring

setting embodying my new design; Fig. 2 is a top plan view; and Fig. 3 is a side elevation.

I claim:

The ornamental design for a ring setting for precious stones, as shown.

BENJAMIN HUCHBERGER.

In presence of—

A. B. CLOTHIER,
J. C. RATNER.
